Walter Soller, Cincinnati, Ohio, assignor of one-half to William H. Woodin, Jr., San Francisco, Calif.; Nora A. Woodin executrix of said William H. Woodin, Jr., deceased

Application August 19, 1943, Serial No. 499,260

6 Claims. (Cl. 315—12)

1

My invention relates broadly to electron tubes and more particularly to a deflection type of secondary electron emission tube for wide application in the electronic industry.

One of the objects of my invention is to provide a construction of deflection type secondary electron emission tube having associated input and output circuits wherein substantially complete isolation of the input from the output circuit is effected.

Another object of my invention is to provide a construction of deflection type secondary electron emission tube having extremely low capacitance across the input circuit for adapting the tube for operation at relatively high frequencies.

Still another object of my invention is to provide a construction of high power deflection type secondary emission tube having provision for voltage amplification proportional to the length of the electron beam path within the tube.

A further object of my invention is to provide a construction of deflection type secondary electron emission tube having low internal resistance and operative at high input impedances to obtain relatively large power output with substantially complete isolation of the output circuit with respect to the input circuit.

A still further object of my invention is to provide an arrangement of electron multiplier system within a deflection type secondary electron emission tube with substantially complete isolation of the input and output circuits.

Another object of my invention is to provide an arrangement of deflection type tube employing secondary electron emission in which the output end of the tube may be applied to various forms of work circuits and remotely controlled from the input end of the tube with substantially complete isolation between the input and output circuits of the tube.

Other and further objects of my invention reside in the construction and arrangement of the elements of deflection type secondary electron emission tubes as set forth more fully in the specification hereinafter following by reference to the accompanying drawings, in which:

Figure 1 is a longitudinal sectional and side elevational view of a deflection type secondary electron emission tube embodying the principles of my invention; Fig. 2 shows the elements of the tube of Fig. 1 in plan arrangement looking down upon the tube of Fig. 1 with the envelope of the tube broken away and illustrated in section to more clearly show the elements therein; Fig. 3 is a transverse sectional view taken on line 3—3 55

2

of Fig. 1; Fig. 4 is a transverse sectional view on line 4—4 of Fig. 1; Fig. 5 is a transverse sectional view on line 5—5 of Fig. 1; Fig. 6 is a transverse sectional view taken on line 6—6 of Fig. 1; Fig. 7 is a transverse sectional view through the electron emitting electrode taken on line 7—7 of Fig. 1; Fig. 8 is an elevational view of the electron emitting electrode with parts broken away and shown in section; Fig. 9 is a schematic view of a modified arrangement of deflection type secondary electron emission tube embodying my invention; Fig. 10 is a schematic view of a further modified form of deflection type secondary electron emission tube embodying my invention; Fig. 11 is a transverse sectional view taken on line 11—11 of Fig. 10; Fig. 12 shows a modified arrangement of the plates which may be employed in lieu of the arrangement illustrated in Fig. 11; Fig. 13 illustrates a further modified form of deflection type secondary electron emission tube embodying my invention; Fig. 14 is a transverse sectional view on line 14—14 of Fig. 13; Fig. 15 is a sectional view taken on line 15—15 of Fig. 13; Fig. 16 shows an alternate arrangement of electrodes as compared to the arrangement of electrodes shown in Fig. 14; Fig. 17 is a sectional view showing the arrangement of electrodes in the alternate form shown in Fig. 16; Fig. 18 shows a further modified form of the tube structure of my invention in which certain of the plate electrodes are substantially elliptical in section for reduction in the electrode edge effects and erratic electron discharges; Fig. 19 is a plan view of the tube illustrated in Fig. 18; Fig. 20 shows an application of the tube of my invention to an amplification system; Fig. 21 illustrates a form of coupling circuit for establishing connection with the elements of the tube of my invention; Fig. 22 illustrates the manner in which the tube of my invention may be associated in circuit with conventional electron tubes; Fig. 23 is a sectional view of the electron tube structure of my invention with an associated electron multiplier system; Fig. 24 is a schematic view illustrating the electron multiplier portion of the tube of my invention; Fig. 25 is a transverse sectional view taken on line 25—25 of Fig. 23; Fig. 26 shows an application of the deflection type secondary electron emission tube of my invention to a positive or negative regenerative circuit; Fig. 27 illustrates a modified form of regenerative circuit which may be employed with the tube of my invention; Fig. 28 illustrates an application of the tube of my invention to an amplification system of the regenerative type; Fig. 29 is a fragmentary view showing an arrangement of magnetic con-

trol which may be employed in the regenerative system illustrated in Fig. 28; Fig. 30 illustrates a modified construction of tube embodying my invention and in which a change in focus of an electronic beam is employed under control of the input circuit for producing changes in the output circuit; Fig. 31 is a transverse sectional view on line 31—31 of Fig. 30; Fig. 32 is a transverse sectional view taken on line 32—32 of Fig. 30; Fig. 33 shows a modified form of tube embodying my invention in which additional grids are utilized for effectively controlling both the deflection of the beam and the quantity of the electrons in the beam; Fig. 34 is a view taken on line 34—34 of Fig. 33 and illustrating the secondary emission electrodes in plan view; Figs. 35 and 36 (Fig. 36 taken on line 36—36 of Fig. 35) illustrate a further modified form of my invention; Figs. 37—39 (Fig. 39 taken on line 39—39 of Fig. 37) illustrate still another modified form of my invention; Figs. 40—42 show a form of my invention employing magnetic control of the electron beam (Fig. 41 taken on line 41—41 and Fig. 42 taken on line 42—42 of Fig. 40); Fig. 43 shows a direct current amplification system embodying my invention; and Fig. 44 shows a direct current magnetically controlled regenerative direct current amplification system embodying my invention.

Referring to the drawings in detail, reference character 1 designates the envelope of the tube provided with terminal members at opposite ends of the tube indicated generally at 2 and 3. The electron beam generator is illustrated as including the electron emitter represented generally at 4, the beam forming plates being shown at 5 and 6 and the deflecting plates indicated generally at 7 and 8. These several elements are suitably supported by wire members extending through the end of the tube and supported in the glass press 13. The secondary electron emission plates are represented at 9 and 10 and illustrated more clearly in Fig. 3. These secondary electron emission plates are triangular in shape and are separated edge to edge by a diagonal gap represented at 11. Auxiliary plates 12 and 14 are arranged adjacent the secondary electron emission plates 9 and 10 and spaced therefrom by narrow gaps represented at 15 and 16. The wire members 9a, 10a, 12a and 14a which support the secondary electron emission plates 9 and 10 and the auxiliary plates 12 and 14 are suitably spaced by an insulation member formed from mica or other suitable material and represented at 17. The wire members 9a, 10a, 12a, and 14a supporting the secondary electron emission plates 9 and 10 and auxiliary plates 12 and 14 extend outwardly from the glass press represented at 18 and through the flat plate of insulation material represented at 17 to the plates 9 and 10 and auxiliary plates 12 and 14. The plate of insulation material 17 extends in spaced substantially parallel relation to the plane of the coplanar secondary emission plates 9 and 10 and auxiliary plates 12 and 14. A structurally rigid assembly is thus provided by the spaced wire members 9a, 10a, 12a and 14a, which extend through the plate of insulation material 17, substantially normal to the plane thereof for a substantial distance on either side of the plane of the plate and are then spread to spaced positions for attachment to the plates 9 and 10 and auxiliary plates 12 and 14 for forming a structurally rigid assembly thereof spaced by narrow gaps 11, 15 and 16 as heretofore explained. The plate of insulation material 17 is substantially of circular contour and of such dimension that the diameter

10
15
20
25

thereof is less than the shortest dimension of the plate system. The plate 17 is of such size that the limits of its dimensions fall substantially within the area covered by the associated triangular-shaped plates.

The electron beam from the emitter 4 is shaped into rectangular cross section as it passes through the slot 19 in the cylindrical member 20 which surrounds the emitter 4 and though the slots 21 and 22 in the beam forming plates 5 and 6, respectively. The beam of rectangular cross section strikes the diagonal plates 9 and 10. These plates are coated with electron emitting material and emit secondary electrons to the auxiliary plates 12 and 14. The external circuits are represented schematically in Fig. 3 as including connections to one of the secondary emitting plates 9 and to one of the auxiliary plates 12 with resistors 23 and 24, shown schematically in circuit.

In Fig. 9 in which I have illustrated a similar plate system, I have shown the circuit in more detail including resistors 24 and 25 connected to secondary electron emitting plates 9 and 10, respectively and connected to the output system. As will be explained in more detail hereinafter, the current through the output resistances 24 and 25 is the difference between the secondary electron current and the current in the direct electron beam. This results in a large current as the secondary electrons are many times larger than the primary electrons in the beam. The greater the current, the greater are the voltages across the resistances.

In Fig. 8 I have shown the details of construction of the emitter from which it will be seen that the heating element 26 extends horizontally through the tubular support of insulation material represented at 27. The tubular support 27 provides a mounting means for the electron emitter which is wound as a spiral wire or ribbon 28 over the tubular member 27. The emitter 28 is confined in position by cylindrical member 29 which is slotted at 19 for the emission of electrons in a substantially rectangular beam. The electron emitting system is compactly mounted in position by means of annular ring members 29 and 30 which embrace opposite ends of the tubular members 27 and 20 with the electron emitting element 28 disposed therebetween. This arrangement of emitting element facilitates replacement of the emitter in the event of rebuilding the tube.

In Fig. 9 I have illustrated a modification of the electron generator portion of the tube wherein the beam forming plates entirely surround the emitter with slots in the beam forming plates registering one with the other for shaping the rectangular electronic beam. That is to say, the beam forming plates are shown at 31, 32 and 33, each including transversely extending slots indicated at 31a, 32a and 33a. A rectangular narrow beam is thus projected between the deflection plates 7 and 8 to bombard the secondary emission plate system 9—10 for secondary emission to auxiliary plate system 12—14 as will be explained more fully hereinafter.

In Fig. 3 I have indicated by dotted lines 9a and 10a the instantaneous area of the plates 9 and 10 respectively, that are swept by the rectangular shaped electron beam.

It will be observed that a steady potential is maintained between the cathode and the beam forming plate 31 as represented at 34. The positive terminal of the direct current source 34 connects to the cathode 28 while the negative terminal of direct current source 34 connects to

beam forming plate 31. A direct current source 35 is provided with its negative terminal connected to beam forming plate 31 and its positive terminal connected to beam forming plate 32. A direct current source 36 is provided with its negative terminal connected to beam forming plate 32 and its positive terminal connected to beam forming plate 33. The circuit is completed from the positive terminal of direct current source 36 to the auxiliary plates 12 and 14 connected together and connected to the positive terminal of direct current source 37, the negative terminal of which connects to the positive terminal of direct current source 36. The circuit is completed from resistors 24 and 25 which respectively connect with secondary emission plates 9 and 10 through conductor 38 to the positive terminal of direct current source 39, the negative terminal of which connects to the first of the beam forming plates 31. The input circuit of the tube connects to terminals 48 while the output circuit for the tube connects to terminals 41.

In lieu of the arrangement of output plates illustrated in Figs. 1, 2, 3 and 9, I may employ an arrangement of plates as illustrated in Figs. 10 and 11 where the secondary electron emission plates are rectangular in shape but are off-set from each other in a vertical plane and spacially related with respect to each other as represented at 42 and 43. The secondary emission plates are separated by a gap 44. The auxiliary plates which receive secondary electrons from the secondary electron emission plates 42 and 43 are represented at 45 and 46 spacially and angularly related to plates 42 and 43 but arranged to receive secondary electrons from plates 42 and 43. The arrangement shown is schematic but illustrates the principles of my invention wherein secondary electron emitting plates 42 and 43 are scanned by the electron beam under control of deflection plates 7 and 8 connected to input circuit 49 for discharge of secondary electrons to auxiliary plates 45 and 46 in a manner similar to the principles of operation of auxiliary plates 12 and 14 described in connection with Figs. 1, 3 and 8. Auxiliary plates 45 and 46 shown in Figs. 10 and 11 are arranged at an angle to the longitudinal axis of the tube. The output current controlled by the secondary emission current is supplied to output circuit 41. The arrangement of the auxiliary plates 45 and 46 and the secondary electron emitting plates 42 and 43 is more clearly represented in Fig. 11.

In lieu of the arrangement of rectangular plates shown in Figs. 10 and 11, I may employ a pair of triangular shaped secondary electron emitting plates shown at 47 and 48 in overlapped spacially related arrangement as shown in Fig. 12. Auxiliary plates 49 and 50 are arranged in overlapping but spacially related positions with respect to the secondary electron emitting plates 47 and 48 and disposed at an angle to the longitudinal axis of the tube like plates 45 and 46 shown in Figs. 10 and 11. The circuit connections are the same as those illustrated in Figs. 9 and 10.

In Fig. 13 I have illustrated an arrangement of electron beam tube having a plate system with variable secondary emission characteristic. The plate system includes a triangular shaped plate member 51 tapering from a straight edge portion to an apex portion 51a. The surface of plate member 51 is covered with secondary electron emissive material and the electron beam emanating from the electron generator effects a release of secondary electrons which are collected by an-

gularly disposed auxiliary plates 52 and 53. An output circuit is completed between the auxiliary secondary electron collecting plates 52 and 53 and the triangular plate member 51 including potential source 58 and output resistance 59. Behind the triangular shaped plate member 51, I arrange the rectangular shaped grid electrode 54 and in spacial relation thereto I provide plate 55. The plate 55 is electrically connected with the triangular shaped plate member 51. A connection is completed between triangular shaped plate member 51 and the grid electrode 54 through the potential source 57. The horizontal electron beam which emanates from the electron generator is as wide as the upper edge portion of the triangular shaped plate member 51 as represented at 51b and as the input across deflecting plates 7 and 8 is changed, the beam deflects vertically in a downward direction scanning the narrow surface of the rectangular plate member 51 accompanied by the release of a smaller number of secondary electrons which travel to auxiliary electrodes 52 and 53. As the electron beam is deflected upwardly due to increased voltage on the input plates 7 and 8, the secondary electrons released from the surface of triangular shaped plate 51 increases from a very small amount adjacent the apex 51a in its lower position to a maximum amount adjacent the upper position approaching the edge portion 51b of the triangular shaped plate 51. The secondary electrons which are emitted from triangular shaped plate 51 vary from 10 to 100 times that of the primary beam but are directly proportional to the amount of the beam striking this plate. Plate 51 acts as an emitter, the amount of emission being controlled by the input on the deflection plates 7 and 8. This emission will cause a current in the circuit including the battery 58 and the load resistance 59. This arrangement therefore becomes a two-electrode tube in which the plate member 51 serves as a cathode and the collecting plates 52 and 53 serve as anodes. The emission of this two element arrangement is controlled by the distant deflection plates 7 and 8 through the medium of the electron beam. That part of the electron beam that does not strike the triangular shaped plate element 51 will pass through the grid electrode 54 and strike plate electrode 55 which is spacially related to grid electrode 54. The secondary electron emission from plate electrode 55 is prevented from reaching auxiliary plates 52 and 53 by the negative potential impressed upon grid electrode 54 from potential source 57. In order to further reduce the possibility of secondary electrons discharging from plate electrode 55 and being collected by auxiliary electrodes 52 and 53, the plate 55 is constructed from a material which does not readily emit secondary electrons while plate member 51 is coated for the particular purpose of producing high secondary electron emission properties.

Fig. 15 is a plan view showing the arrangement of the electrodes illustrated in Figs. 13 and 14. An alternate arrangement of electrodes may be provided as shown in Figs. 16 and 17 wherein the plate member 56 constituting the target for the electron beam has a triangular shaped central cut-out portion through which the electron beam is propagated. Thus a pair of triangular shaped surfaces are provided for the plate member 56, each of which are coated with secondary electron emissive material. This arrangement enables secondary electrons to be more readily released

from plate member 56 and reach auxiliary plates 52 and 53. The grid electrode 54 and plate electrode 55 are arranged as before in spacial relation to plate member 56. The tendency for electrons to leave plate electrode 55 is less because of its great distance and shielding by plate member 56 while the field drawing electrons from plate member 56 is increased by this arrangement. Fig. 17 shows the arrangement of the output resistance 59 in such position that connections may 10 readily be made thereto to a succeeding three-electrode electron tube or further electron beam tube stage.

In Figs. 18 and 19, I have shown a modified arrangement of electron beam tube having a 15 special arrangement of auxiliary plate system for collecting the secondary emission. The auxiliary plate system is formed and shaped to eliminate sharp edges wherever a concentration of field strength exists. By shaping the auxiliary plates in elliptical section and providing coacting pairs of plates as represented at 61, 62, 63 and 64, the field strength around the plate system is rendered uniform and excessive concentrations of field strength are eliminated. As a further 20 precautionary measure for reducing edge effects and erratic electron discharges, the plate member 51 is rounded at its edges. The auxiliary plates 63 and 64 also serve to shield the electron beam from any possible transverse field across 25 collector plates 61 and 62. This form of tube is highly practical for use in all of the various circuit arrangements heretofore employing conventional control grid tubes with the added advantage that reactionary effects between the control system and the output circuit are substantially 30 eliminated. For example, the electron beam tube of my invention such as represented in Figs. 18 and 19 is applicable to the entire field of electronics including all forms of amplifiers represented for example, in Figs. 20, 21 and 22.

In Fig. 20 the input circuit 40 leading to deflecting plates 7 and 8 may connect to any circuit upon which feeble currents are impressed for purposes of amplification. Current at increased amplitude corresponding in wave form to the impressed current is delivered from the plate system 61-62 through battery 58 to the primary winding 65 of transformer 66 to the secondary output winding 67 leading to output circuit 68. The output circuit 68 may connect to a succeeding stage of deflection type tube or a grid controlled tube.

The electron beam tube of my invention is accordingly applicable to regenerators, oscillators, feed-back circuits, reverse feed-back circuits, D. C.-A. C. amplification systems and various forms of frequency multipliers or frequency division systems. The outstanding advantage of the electron beam tube of my invention is complete isolation of the input circuit from the output circuit to meet such conditions, for example, as low power input, high voltage amplification, high sensitivity operation or operation at high frequency. This isolation feature permits large voltages on the output with no possibility of the output voltages affecting the input; extremely low impedance not possible in the conventional grid controlled tube; and sensitivity even with large output currents.

The electron stream has input forces applied at right angles to its path rather than directly in it as is the case in a grid controlled tube. There is less influence of the stream on the input producing these forces. The feature of this input

causing the control of the emission in a remote set of elements gives the tube of my invention a fundamental advantage in the art.

5 In Fig. 21 I have shown an arrangement of capacitance resistance coupling which may be substituted for the transformer coupling illustrated in Fig. 20 in the output circuit of the electron beam tube system. Coupling resistor 69 arranged in the output circuit of the electron beam tube is capacitively coupled with coupling resistor 70 for connection to the next succeeding utilization stage through coupling capacitors 71 and 72. The coupling resistance 70 may connect to the input circuit of a succeeding deflection type tube or to a conventional electron tube stage of the grid control type.

20 Fig. 22 shows the application of the electron beam tube system of my invention to a direct current amplification system in which the output circuit of the electron beam tube including potential source 58 and output resistor 59 connects to the input circuit of a direct current amplifier comprising tube 73. Tube 73 includes cathode 73a, control grid 73b and anode 73c arranged as shown. The cathode is supplied with power from battery system 74 through resistors 75 and 76. The output resistance 59 in series with potential source 58 in the output circuit of the electron beam tube connects to control grid 73b and cathode 73a through resistance 76. The output circuit of tube 73 connects from anode 73c through resistance 77 and to the potential source 74 as shown. Various modifications of the arrangement for coupling the output of the electron beam tube with the input of a grid control tube may also be employed.

25 In Fig. 23 I have shown my invention applied to an electron multiplier type of tube. In this arrangement the secondary emission plate system is formed by a plate-like envelope 78 folded 30 upon itself with the front and rear portions of the envelope spaced from each other for enclosing the grid element 80 therein. The secondary electron emitting portions of the plate system 78 are 35 represented at 79, having a V-shaped cutout therein for controlling the secondary electron emission as the area of the plate is swept by the electron beam. The portions 79 of the plate meet at the apex portion 79a of the V-shaped cutout. The grid 80 is shown disposed behind the portions 40 79 of the plate system. In order to effectively direct the secondary electron emission from portions 79 of the plate system, I arrange shields 79b and 79c adjacent the peripheral edges of the plate 45 system in a position for shielding electronic discharge in the direction of any of the multiplier plates other than the sets of multiplier plates 81 and 81'. A plurality of multiplier plates are arranged in the trajectory of secondary electrons 50 initially discharged from multiplier plates 81 and 81'.

55 I have shown more clearly in Fig. 24 the plurality of multiplier plates at 82, 83, 84, 85, 86 and 87, with complementary plates arranged at 82', 83', 84', 85', 86' and 87' for receiving a secondary electron emission from each of the successive plates of the series. The secondary emission emitted from one plate is directed to a succeeding plate as indicated by the arrows and will not pass 60 to any other plate; that is, each plate although it is a secondary electron emitting plate also acts as a shield for the projection of electrons along the trajectory indicated by the arrows. The circuits for the several multiplier plates are shown 65 in Fig. 23 wherein the pairs of complementary

plates are interconnected and biased at differing positive potentials obtained from potential source 58 shunted by potentiometer 88 having taps distributed thereon, as shown. That is, sets of plates 81—81' are connected to tap 88a; sets of plates 82 and 82' are connected to tap 88b; sets of plates 83 and 83' are connected to tap 88c; sets of plates 84 and 84' are connected to tap 88d; sets of plates 85 and 85' are connected to tap 88e; sets of plates 86 and 86' are connected to tap 88f; while sets of plates 87 and 87' connect to the output for delivering the multiplied output current. The progressive positive potentials which are applied to the plates 81—87 and 81'—87', respectively, are such that there is a continued tendency for the secondary emission from the successive plates to travel in the paths indicated to the final output plates 87 and 87' for multiplying at each plate the final multiplied current from 87 and 87' delivered to the output circuit 41. Each of the surfaces of the multiplier plates are coated with secondary electron emitting material except plates 87 and 87' to insure the maintenance of high secondary electron emitting properties.

While various secondary electron emitting materials may be employed, I desire to designate particularly the use of caesium-activated beryllium-beryllium oxide, and rubidium-activated silver-silver oxide. The means for generating the electron stream or beam are similar to that illustrated in connection with Figs. 9 and 13, and for purposes of designating the electron beam generator, I have indicated the assembly at G. The flat-ribbon like electron beam emitted by G is controlled in position by deflecting plates 7 and 8 in accordance with the control currents applied at input circuit 40 and sweeps the secondary electron emitting triangular shaped plates 79. The secondary electrons released from the triangular shaped plates 79 strike plates 81 and 81' along paths designated by the arrows in Fig. 24 but are prevented from striking the successive multiplier plates by shields 79b and 79c, and by the shielding effect between rear surfaces of each of the plates except along the discharge paths indicated by the arrows in Fig. 24. The operation of the secondary electron multiplier is as follows: The current is increased at each successive plate in the ratio of the secondary emission to the electrons striking it. The final plates 87—87' are not composed of secondary electron emitting material. Therefore, the current due to all the electrons striking the plates is passed on from these plates into the output resistance 59. By this means, the output is amplified approximately by the product of the number of secondary emitting plates and the ratio of the secondary emission plates and the ratio of the secondary emission to primary electrons.

In Fig. 26 I have shown the principles of my invention applied to both positive and negative feedback systems. The input circuit 40 connects across an adjustable resistance 89 connected in series with a feedback regulating resistance 90, both of which are connected to the deflecting plates 7 and 8, as shown. The generator of electrons is designated generally at G.

The circuit which includes the anode system 51—55 is similar to that explained in connection with Figs. 9 and 13, etc., except that a connection is taken from the anode system through a conductor to an intermediate position between adjustable resistors 89 and 90. By adjusting the relative values of resistors 89 and 90 and also

the value of the output resistor 59, which in this instance is shown as adjustable, the amount of feedback can be regulated to any desired quantity. By reversing the terminals shown on the diagram, the positive feedback can be changed to negative feedback. Because the battery supplies 37, 57 and 58 are reversible in the arrangement illustrated in Fig. 26, I have not restricted the polarities in the illustration.

10 In Fig. 27 I have schematically shown the substitution of a magnetic control in the input circuit for the electrostatic control illustrated in Fig. 18. I have indicated a pair of magnetic coils 91 and 92 connected in place of input 7—8 and connected in series by conductor 93 for influencing the electron beam generated by beam generator shown. The output circuit is designated schematically at 41 associated with the tube in a manner similar to that explained in connection with Fig. 26.

15 It will be understood that similar forms of magnetic control may be employed with the electron multiplier type of tube illustrated in Figs. 23—25 and that in all cases the advantageous features of 20 the tubes illustrated in the different figures may be combined to produce the most advantageous results in the electron beam tube.

25 In Fig. 28 I have shown the electron beam tube of my invention applied to a transformer type of 30 the generator circuit by which either feedback or oscillations can be produced. The input circuit to the tube of Fig. 28 connects to deflecting electrodes 7—8 for controlling the scanning of the anode system 51—55 under the influence of 35 deflecting plates 7—8. The circuit across deflecting plates 7—8 is tuned by adjustable condenser 99 connected in the circuit leading to coupling coil 98 in series with adjustable resistance 100. The coupling coil 98 is adjustably 40 coupled with inductive winding 97 disposed in the output circuit of the secondary electron emitting plate 51, which also includes primary winding 95 of coupling transformer 94 in series with inductive winding 97 and potential source 58 and anode 45 systems 61—62. The coupling transformer 94 has the secondary winding 96 thereof coupled to primary winding 95 and connected to the output circuit 41. Output circuit 41 may connect to any 50 succeeding amplifier or utilization circuit including a deflection tube stage. The condenser 99 in the input circuit permits tuning to selected frequencies and the adjustable resistance 100 permits the control of the phase of the feedback current until synchronism of the movement of the 55 deflection beam and the frequency of the feedback current is obtained. The amount of coupling between 97 and 98 may be changed and by controlling the tuning through condenser 99 and the phase of the circuit through adjustable resistance 100, the regenerative properties of the 60 circuit may be so adjusted that the tube will commence self-oscillation.

65 The same type of circuit, although shown as a radio frequency regenerative and oscillator circuit, can also be used in the audio and ultra-high frequency ranges. The low capacitance of the input will allow this application to extremely high frequencies. Although this is shown just as an inductively coupled regenerative or oscillating circuit, it is not intended to be limited to that. It can also be adapted to capacitance coupled regenerative and oscillating circuits.

70 In lieu of the electrostatic controlled method by deflection plates 7—8, I may employ a magnetic control system, as illustrated in Fig. 29

wherein the input circuit 40 connects to magnetic control windings 91 and 92 associated with the electron beam. The regenerative circuit associated with the anode system 61-62 which I have represented at 103, including tuning condenser 99, connects to regenerative coupling coils shown at 101 and 102 arranged in coupled relation to the coils 91 and 92 for establishing a magnetic feedback between the several windings. Regenerative and oscillating currents are thus established. The electron beam generation arrangement may be of the same type as heretofore explained and shown schematically in Fig. 29.

In Figs. 30-32 I have shown the system of my invention applied to an electron beam amplifier tube. I have termed this an electron beam amplifier tube rather than a deflection tube because in this arrangement I provide an electron beam generator of the electron gun type schematically represented at 104, which propagates an electron beam of circular section through the apertured electrodes 105 and 106. Apertures are indicated at 105a and 106a. The apertured electrodes 105 and 106 are curved as shown, and are connected to the input circuit 40 and serve as focusing electrodes for the electron beam propagated from electron gun 104. As the current changes in the input circuit 40, the beam is caused to change from an accurate focus to an out of focus condition. The electron beam is directed toward the disc-like secondary electron emitting plate member 108, centrally apertured at 108a. The disc-like secondary electron emitting plate 108 is surrounded by a toroidal shaped hooded collecting electrode 109, shaped as indicated. The electrode 109 also encloses grid electrode 54 and is spacially related to plate electrode 55. The electron beam striking plate electrode 55 when drawn over against disc-like secondary electrode 108 causes the emission of secondary electrons that are drawn over to the toroidal shaped hooded electrode 109. The original beam is circular in cross section as it is formed and it is propagated from electron gun 104 and passes through the apertures 105a and 106a in focusing electrodes 105 and 106 and through apertures 108a and electrode 108.

The potential on the two input plates 105 and 106 allows the beam to focus exactly in the center of the plate 108 and, therefore, passes through the aperture 108a in plate 108 and strikes plate electrode 55. Any secondary electrons which would be emitted remain there because grid 54 is held at a negative potential by battery 57. As the input increases the beam of electrons is thrown out of focus by the voltage on the two circular spherical shaped plates 105 and 106. This changes the focus of the beam so that it now does not focus in the aperture 108a in the plate 108 but is spread out as it strikes plate 108. The extent of this spreading out is controlled by the input potentials on plates 105 and 106. In this way a similar result is obtained as with the deflection method, although I do not limit my invention to deflection and can use any means by which a change in emission from plate 108 can be secured to the output circuit. Accordingly it will be understood that my invention is not restricted to a rectangular cross section beam but is equally applicable to a circular section beam.

In Figs. 33 and 34, I have shown an arrangement of deflection type tube in which a control grid 107 is introduced in the electron beam generator assembly and connected to a separate control circuit including the input resistance 110 and the source of potential 111. In this arrange-

ment of electron beam tube a second input circuit may be connected at 112 for control of the electron beam tube at 112 rather than across the deflection plates 7 and 8. The anode system is connected in the same manner as heretofore described. The amount of electrons in the electron beam may thus be changed by slight changes in the input circuit connected to input terminals 112. The electron beam tube may thus be controlled by either varying the deflection of the electron beam or controlling the quantity of electrons in the beam. This allows this type of tube to be used in a modulating circuit where either input 112 or 40 can be used as the higher frequency and the other as a modulating frequency.

It is desired to have the output of the tube be a function of the product of two quantities. The output of this circuit which is affected from the emission of the output emitting element 31 which is actually its cathode is governed by the total amount of electrons striking the cathode. The amount of electrons striking this plate will be controlled by the total amount of electrons of the beam that is, density of beam, controlled by grid input 112, and the amount of the cross section of the beam that strikes the plate 51-55 which is controlled by input 40, that is the deflection plates 7-8. Therefore, the secondary electron emission will be proportional to the product of both voltages on input 112 and input 40. This in turn will cause a voltage across the output resistance 53 to be proportional to this same product.

I have designated the two inputs as "input 1" and "input 2" to show that either or both may be used in accordance with the requirements of the circuit.

In Figs. 35 and 36 I have shown my invention applied to an electron beam tube in which an electron beam of circular section emanating from electron gun 104 may pass through an enlarged aperture 115 in the disc-like secondary electron emitting plate 114 and be displaced under control of deflection plates 7-8 to strike the annular face of plate 114 for release of secondary electrons to the toroidal shaped hooded plate 109. The structure illustrated in Figs. 35 and 36 differs from the structure described in Figs. 30-32 by reason of the enlarged aperture 115 in plate 114. Greater sensitivity is obtained by enlarging the aperture in plate 114 as a large change in secondary emission is secured by a slight change in the deflection of the beam. The arrangement of the electrodes in tubes 35 and 36 and the circuits interconnecting said electrodes are similar to the arrangements shown in Figs. 30-32.

In Figs. 37-39, I have illustrated an electron beam tube of high sensitivity in which a flat electron beam of rectangular section normally passes directly through a rectangular aperture 117 in secondary electron emission plate 116 for zero input. A slight deflection of the beam produced by a small input between plates 7-8 with this construction will cause a relatively large portion of the beam to strike plate 116 causing a correspondingly large secondary emission from it. This construction is illustrated because it provides greater sensitivity than the triangular opening construction shown in previous tubes. It will not, however, operate through as large a deflection of the beam. This greater sensitivity is caused by a large change in secondary emission produced by a slight change in the deflection of the beam.

In Figs. 40, 41 and 42 I have shown a construction of tube in which a magnetic control system is employed for deflecting the beam. The

magnetic control system is a coil structure 120 of magnetic alloy having pole pieces 118 and 119 terminating in a magnetic gap 121 through which an electron beam from electron beam generator G of the type heretofore explained is propagated. The magnetic control system operates to control the displacement of the electron beam. The magnetic alloy core concentrates the magnetic field to substantially the thickness of the electron beam irrespective of the size of the control windings at the gap where the magnetic circuit passes through the beam as shown more clearly in Fig. 41. The magnetic control system includes an input winding 123 connected to input circuit terminals 40 and a regenerating winding 124 which connects to the anode system as shown.

With the construction of core 120 as shown, several coils can be caused to affect the magnetic field and so better facilitate feedback and balancing arrangements with deflection beam tubes. In this circuit alternating current signal energy is employed. The output transformer 125 is arranged so that the current produced in an additional secondary coil 126 can be fed back into the independent coil 124 from that through which the input current passes. Winding 124 is wound on the core 120 of the magnetic deflecting unit. By this means an entirely independent positive or negative feedback can be obtained. The positive feedback will give greater amplification than can be produced without the feedback, while the negative feedback will produce stability of operation of the tube and circuit. Resistance 131 is provided in circuit between control winding 124 and secondary coil 126 to adjust the phase of the feedback to synchronize with the deflection of the beam. The output from the cathode system 51-62 and plate electrodes 51-55 is supplied to primary winding 126 by transformer 125 by which a portion of the energy is transferred through winding 128 to the magnetic control winding 124. Secondary winding 127 leads to the output circuit designated at 41.

Fig. 43 shows a tube that is similar to the tube of Figs. 30-32 except that it allows the feedback feature to be accomplished for D. C. signals. The current in the output circuit is fed directly back through the second coil 124 of the magnetic deflecting unit through phase resistor 131. By using suitable connections and by the relative direction of the winding of the two coils 123-124 on the core either positive or negative feedback, even on D. C. operation, is obtained. Very small D. C. voltages can be amplified with this arrangement and the higher sensitivity and stability of positive and negative feed back systems can be obtained. There is a decided advantage in this independence of feedback in these deflection amplifying tube systems. This circuit is adapted to thermocouple and thermopile voltage amplification as it is a voltage sensitive D. C. amplifier.

The shield 129 around the tube 1 is of high permeability material so that external electric and magnetic fields will not disturb the operation of the tube. As both shield 129 and core 120 are of high permeability material and the core 123 is entirely inside and away from the shield, the magnetic field will remain in the core 120 and thereby go through the electron beam rather than into the shield. The shield 129 and core 120 are both grounded as shown. All other forms of tubes shown in the several figures can be shielded similarly where high sensitivity is required and protection against external fields is needed.

In Fig. 44 I have shown the arrangement of the tube system of Fig. 43 with an additional direct current amplifier of the conventional type. The direct current amplifier is designated as having parts similar to the parts represented in Fig. 22 with the grid cathode circuit connected to the resistance 59 in the output circuit of the anode system of the deflection tube. A direct current power supply for the power supply circuits of tube 73 is connected at 130.

The output current of this amplifier is fed back into the second coil 124 on the magnetic deflection core 120 through phase adjusting resistor 131. The operation of the tube of Fig. 44, is similar to that shown in Fig. 43, and when negative feedback is used, even greater stability is accomplished than with that of circuit in Fig. 43. Fig. 44 is not restricted to the application of the invention to one amplifier stage but any number of stages of amplifiers and the current in the last stage is fed back into the second coil 124 of the magnetic core. The larger the amplification, the greater will be the stability. Also if it is positive feed back, this arrangement will give even greater amplification. The tube of Fig. 44 employs the principle of controlled emission in the output part of the tube in which feedback is employed.

The subject matter of Figs. 23 and 24 herein is now set forth in my copending divisional application Serial No. 551,513, Electron tube, filed August 28, 1944, now U. S. Patent 2,458,539, issued January 11, 1949; the subject matter of Figs. 30-32 and 35 and 36 herein is set forth in my copending divisional application Serial No. 551-514, Electron tube, filed August 28, 1944; the subject matter of Figs. 40-41 herein is now set forth in my copending divisional application Serial No. 551,699, Electron tube, filed August 29, 1944, now U. S. Patent 2,456,654 issued December 21, 1948.

While I have described my invention in certain preferred embodiments, I realize that modifications may be made in the arrangement and method employed and I desire that it be understood that no limitations upon my invention are intended other than may be imposed by the scope of the appended claims.

What I claim as new and desire to secure by Letters Patent of the United States is as follows:

1. An electron tube system comprising an evacuated vessel, an electron discharge device for propagating an electron beam through said vessel, a pair of angularly related spacially disposed flat plane-like electrodes mounted on opposite sides of a longitudinal axis within said vessel for controlling the angular sweep of the electron beam, a plate system comprising a multiplicity of coplanar sections, a plate of insulation material mounted in spacial relation to the rear of said plate system, a glass press in the end 60 of said tube, wire members individual to each of said plate sections extending from said glass press into said tube and through said plate of insulation material and spaced thereby, said wire members being connected with said plate sections for supporting said sections in coaxing relation in the path of the sweep of the electron beam, two of said coplanar sections varying in linear dimension from a maximum to a minimum at opposite ends of the limits of sweep of the electron beam and having electron emitting coatings thereon for emitting secondary electrons under action of said electron beam, and means for maintaining others of said sections at potentials for receiving the secondary electrons liberated by the aforesaid sections.

2. An electron tube system comprising an evacuated vessel, an electron discharge device for propagating an electron beam within said vessel, a pair of angularly related spacially mounted flat plate-like electrodes for controlling the angular sweep of the electron beam, a plate system comprising a multiplicity of substantially coplanar sections mounted in edge to edge, spacial relation, a plate of insulation material mounted in a plane offset from the rear of the plane of said coplanar sections and electrically connecting and supporting wires extending through said plate of insulation material and attached to the respective coplanar sections of said plate system for maintaining said sections substantially normal to an axis through said electron discharge device in the path of the sweep of the electron beam, certain of said sections having electron emitting coatings thereon for emitting secondary electrons under action of said electron beam and means for maintaining others of said sections at potentials for receiving the secondary electrons liberated by the aforesaid sections.

3. An electron tube system comprising an evacuated vessel, an electron discharge device for propagating an electron beam within said vessel, a pair of angularly related spacially mounted flat plate-like electrodes for controlling the angular sweep of the electron beam, a glass press in the end of said tube, a multiplicity of wire members projecting from said press interiorly of said tube, a plate of insulation material forming spacing and supporting means for said wire members, a plate system comprising a multiplicity of plate sections supported by the wire members extending through said plate of insulation material in the path of the sweep of the electron beam, said sections being arranged in pairs, the sections of one pair each being substantially coplanar and triangular in shape with the hypotenuse thereof extending diagonally across the central axis of the sweep-path of said electron beam and the other pair of sections being spacially related to the aforesaid pair of sections, said first mentioned substantially coplanar pair of sections having electron emitting coatings thereon for emitting secondary electrons under the action of the electron beam and means for maintaining said second mentioned pair of sections at potentials to receive the secondary electrons liberated by said first mentioned pair of coplanar sections.

4. An electron tube system comprising an evacuated vessel, an electron discharge device for propagating an electron beam within said vessel, a pair of angularly related spacially mounted flat plate-like electrodes for controlling the angular sweep of the electron beam, a glass press in the end of said tube, a multiplicity of wire members projecting from said press interiorly of said tube, a mica sheet extending in a plane substantially normal to said wire members, a plate system comprising a multiplicity of plate sections supported by the wire members extending through said mica sheet in the path of the sweep of the electron beam, said plate sections being arranged in pairs, the sections of one pair being substantially coplanar and triangular in shape with the hypotenuse thereof extending diagonally across the central axis of the sweep-path of said electron beam, and the other pair of sections being spacially related to the aforesaid pair of sections, said first mentioned pair of coplanar sections having electron emitting coatings for emitting secondary electrons under the action of

the electron beam, and means for maintaining said second mentioned pair of sections at potentials to receive the secondary electrons liberated by said first mentioned pair of coplanar sections.

5. An electron tube system comprising an evacuated vessel, an electron discharge device for propagating an electron beam within said vessel, a pair of angularly related spacially mounted flat plate-like electrodes for controlling the angular sweep of the electron beam, a plate system comprising a multiplicity of substantially coplanar sections mounted in edge to edge, spacial relation, a substantial circular sheet of insulation material having a diameter less than the shortest dimension of said plate system and mounted in a plane offset from the rear of the plane of said coplanar sections, and electrically connecting and supporting wires extending through said substantial circular sheet of insulation material and attached to the respective coplanar sections of said plate system for maintaining said sections substantially normal to an axis through said electron discharge device in the path of the sweep of the electron beam, certain of said sections having electron emitting coatings thereon for emitting secondary electrons under action of said electron beam and means for maintaining others of said sections at potentials for receiving the secondary electrons liberated by the aforesaid sections.

6. An electron tube system comprising an evacuated vessel, an electron discharge device for propagating an electron beam within said vessel, a pair of angularly related spacially mounted flat plate-like electrodes for controlling the angular sweep of the electron beam, a plate system comprising a multiplicity of substantially coplanar sections mounted in edge to edge, spacial relation, one pair of said sections being substantially triangular in shape and another pair of said sections being substantially rectangular in shape with said rectangularly shaped sections bordering said triangularly shaped sections, a plate of insulation material having dimensions within the limits of the dimensions of said triangularly shaped plates and offset in a plane in the rear of said sections and electrically connecting and supporting wires extending through said plate of insulation material and attached to the respective coplanar sections of said plate system for maintaining said sections substantially normal to an axis through said electron discharge device in the path of the sweep of the electron beam, certain of said sections having electron emitting coatings thereon for emitting secondary electrons under action of said electron beam and means for maintaining others of said sections at potentials for receiving the secondary electrons liberated by the aforesaid sections.
